Design No. 19,912, dated June 17, 1890.

UNITED STATES PATENT OFFICE.

JOHN E. TIBBETTS, OF BROCKTON, MASSACHUSETTS, ASSIGNOR OF ONE-HALF TO CHARLES S. PIERCE, OF SAME PLACE.

DESIGN FOR A SHOE.

SPECIFICATION forming part of Design No. 19,912, dated June 17, 1890.

Application filed March 10, 1890. Serial No. 343,441. Term of patent 7 years.

To all whom it may concern:

Be it known that I, JOHN E. TIBBETTS, a citizen of the United States, residing at Brockton, in the county of Plymouth and State of Massachusetts, have invented and produced a new and original Design for Low-Quartered Shoes, of which the following is a full, clear, and exact specification, reference being made to the accompanying photographic drawings, in which—

Figure 1 is a perspective view looking at one side of the shoe. Fig. 2 is a similar view looking at the opposite side of the same.

The object of this design is to provide a novel, handsome, and attractive low-quarter shoe; and the leading features of the design reside in the instep parts or center vamp-sections having eyelets and lacing, the side gores inclining downward toward the toe, and the side vamp-pieces having ornamental top edges, substantially straight for a part of their length and convex across the gores, as shown.

In the drawings, the numeral 1 indicates the quarter; 2, the sole; 3, the instep parts or center vamp-sections, having eyelets 4; 5, the side vamp-pieces; 6, the toe-piece; 7, the lacing, and 8 gores inclining downward from the top edge 9 of the low-quarter shoe in a direction toward the toe thereof. The side vamp-pieces have ornamented top edges, substantially straight at 10 and convex at 12 across the gores, terminating at the instep part 13 of the sole. The edges 14 of the quarter 1 and the edges 15 of the instep parts or center vamp-sections 3 incline downward toward the front of the shoe.

What I claim is—

The design for a low-quarter shoe, substantially as shown and described.

JOHN E. TIBBETTS.
